COLLAR STAY

Ben E. Manaster, Chicago, Ill., assignor of one-half to Charles I. Greener, Chicago, Ill.

Application October 1, 1942, Serial No. 460,381

7 Claims. (Cl. 2-132)

This invention relates to a collar stay to be used with soft shirt collars and has as its principal object the provision of an improved construction of this character which will be simple in assembly, economical in manufacture, and highly efficient in use.

Another object of this invention is to provide in collar stays a novel leg assembly which will facilitate the arrangement of the collar stay on collar wings of various lengths.

A further object of my invention is to provide in collar stays an improved extendible leg structure which consists of a minimum number of parts which are simple and easily assembled.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a front elevational view of a collar stay illustrating its relative position with respect to a collar and tie which are shown in phantom by dotted lines;

Fig. 2 is a fragmentary elevational view of the collar stay, partly in section, showing the extendible leg portion in compressed condition;

Fig. 3 is a fragmentary perspective view of the upper end of an extendible leg portion showing a stop element about to be assembled thereon;

Fig. 4 is a view similar to that of Fig. 3 with the stop element affixed to the leg portion and an expansion spring disposed thereagainst;

Fig. 5 is a fragmentary perspective view, complementary to that of Fig. 4 and illustrating the general assembly at the lower end of the leg portion;

Fig. 6 is a modified form of assembly for the lower end of the leg portion; and

Fig. 7 is a perspective view of the modified form shown in Fig. 6.

Referring to the drawing, Fig. 1 shows a U-shaped collar stay 10 constructed of a wire element 9 having a crossbar 11 at the ends of which are provided upstanding extensions or humps 12, the opposite ends of which humps 12 are bent as at 13 to extend the remaining length of wire 9 parallel with respect to each other to provide parallel arm portions 15. These parallel arm portions 15 form a part of extendible legs 16 for the collar stay which include movable leg members 17 disposed to move longitudinally relative to the parallel arm portions 15.

The leg members 17 are constructed of a wire

element similar to the wire element 9 and have their lower ends formed into a convoluted loop 18 with the terminal 19 of the leg member extending through the loop 18 and being pointed as at 20 to facilitate piercing of the fabric in the wing of the collar with which it is to be associated. Each leg member 17 is mounted for movement relative to the parallel arm portion 15 with which it is associated, and this is accomplished by forming a loop 21 at the upper end of the leg member 17, said loop 21 being at right angles with respect to the loop 18 and being bent laterally at ninety degrees with respect to the leg member 17 to dispose the loop 21 in a horizontal position.

The extendible leg 16 is so constructed as to make for ease of assembly and to require a minimum number of operations. To this end a stop member 22 is slid over the free end of the parallel arms 15, and this stop member is held snugly against the bend 13 at the hump 12 and flattened down upon the arm 15 by means of a hammer or a vice so that the stop member 22 will remain in gripping relation to the arm 15. It will be noted that the particular form of a stop 22 is a helical spring 23 which is coiled out of a wire element similar to wire element 9. The next step in the assembly of leg 16 is to dispose an expansion spring 24 of predetermined length over the arm 15 with the leading end of the spring 24 engaging the stop 22. The horizontal loop 21 at the upper end of the movable leg member 17 is slid over the arm 15 and lastly an anchorage collar 25 disposed over the free end of the arm 15. This collar 25 is likewise formed by helically coiling a wire element 26 which is caused to grip and hold fast to the arm 15 by a flattening operation.

Means for guiding the leg member 17 for movement in a plane parallel to the long axis of the arm 15 comprises an eyelet 27 formed at the lower end of the arm 15. This eyelet in the preferred form is shown as being wrought from an end portion 28 of the helically formed collar 25. The end portion 28 is bent as shown in dotted lines in Fig. 5 (clockwise) around the shank of the leg member 17 to form a loop to the outside of the arms 15, thus cooperating with the horizontal loop 21 at the upper end of the leg member 17 to guide the leg element for sliding movement in a plane parallel to the long axis of said arm portion 15.

The offset relationship between the arm portion 15 and the leg member 17 plus the fixed relation of the eyelet 27 with respect to the arm portion 15, assures that the point 20 of the leg

member 17 will at all times face that side of the collar stay which lies against the underside of the collar wings. As a further assurance of an alignment between the arm portion 15 and the movable leg member 17, the extremity of the arm portion 15 may be flattened as is shown in Figs. 1 through 5, while the horizontal loop 21 is made oval shape as shown in Fig. 5 to prevent its rotation about the arm portion 15.

A modification of the eyelet 27 is shown in Figs. 6 and 7 wherein the eyelet 27 is formed of an extended portion 29 of the arm portion 15, which extended portion 29 is bent laterally of the arm 15 after the stop 22, expansion spring 24, the loop 21, and the anchorage collar 25 have been placed on the arm portion 15. The extended portion 29 is then bent clockwise as shown in Fig. 6 to embrace the shank of the leg member 17, thus completing the eyelet 27. With this form of eyelet, it will be observed that any form of tubular member may be employed for the stop 22 as well as the collar 25 as long as there is provided a sufficient base against which to rest the expansion spring 24 and as long as a sufficient spacer is provided between the loop 21 and eyelet 27 to aid in guiding the loop 21 relative to the arm 15.

As shown in Fig. 2, the extendible legs 16 are readily foreshortened by urging the point 20 upwardly to compress the expansion spring 24, thus adapting the legs 16 for various lengths of collar wings. Other forms of juncture between the crossbar 11 and the parallel arm portions 15 may be employed in lieu of the hump 12 shown, and by the same token the pointed end 20 of the movable leg element may be a form of stop other than on a convoluted loop so long as the juncture and form of stop perform their respective functions, it being pointed out the the construction and mode of assembly of the extendible legs is the improvement over former structures of this type.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a collar stay having leg portions and leg members movable relative to said leg portions, means mounting said movable leg members on said leg portions for movement relative thereto, said means comprising a loop formation on said leg member and surrounding said leg portion, an eyelet formed at the extremity of said leg portion and surrounding said leg member, and means on said leg portion for projecting said leg members in an extended position.

2. In a collar stay having leg portions and leg members movable relative to said leg portions, means mounting said movable leg members on said leg portions for movement relative thereto, said means comprising a loop formation on said leg member and surrounding said leg portion, an eyelet formed at the extremity of said leg portion surrounding said leg member, and means on said leg portion for projecting said leg members in an extended position, said leg portion providing parallel side faces and said loop formation

being flattened into substantial oval shape to retain said leg member in alignment with said leg portion.

3. In a collar stay of U shape having extendible leg portions, said extendible leg portions including parallel arms on said collar stay, movable leg members arranged for longitudinal movement relative to said parallel arms, means mounting said leg members relative to a corresponding one of said arms, said means comprising a convolution at the upper end of said leg member and disposed at right angle to the long axis thereof and arranged for sliding movement on said arm, an eyelet at the extremity of said arm and disposed at right angle with respect thereto and embracing said leg member, and means on said arm and engaging said convolution to urge the latter and said leg member toward the extremity of said arm.

10 4. In an extendible leg for a collar stay having parallel leg portions extending from a common cross bar, the combination of a stop arranged on said leg portions adjacent the juncture with said crossbar, an expansion spring disposed on said leg portion, a movable leg element having a pointed end and a looped end with the latter end disposed over said leg portion into abutment with said expansion spring, an anchorage collar affixed to the lower end of said leg portion, and an eyelet extending laterally therefrom and embracing said movable leg element to cooperate with the looped end thereof to guide the leg element for longitudinal movement relative to said leg portion.

20 5. In an extendible leg for a collar stay having parallel leg portions extending from a common crossbar, the combination of a stop grippingly engaging said leg portions adjacent the juncture with said crossbar, an expansion spring disposed on said leg portion, a movable leg element having a pointed end and a looped end with the latter end disposed over said leg portion into abutment with said expansion spring, an anchorage collar gripping the lower end of said leg portion, and an eyelet extending laterally therefrom and surrounding said movable leg element to cooperate with the looped end thereof, said leg portions being formed to provide flattened parallel side faces, said looped end of the leg element being oval in shape to guide the leg element for longitudinal movement relative to said leg portion.

30 6. In an extendible leg for a collar stay having parallel leg portions extending from a common crossbar, the combination of a stop formed on said leg element adjacent said crossbar, a compression means disposed on said leg element and bearing against said stop, a movable leg member having a fabric engaging end portion at one end thereof and a laterally extending portion at its other end, said leg portions being formed to provide substantial face portions upon its outer surface, a slot formed in the laterally extending portion of said movable leg member and corresponding in contour to the outer surface of said leg portions and disposed over the latter into engagement with said compression means, and an abutment formed at the free ends of said leg portions to retain the laterally extending portion of said movable leg member on said leg portion.

40 7. In an extendible leg for a collar stay having parallel leg portions extending from a common crossbar, a stop formed on said leg element adjacent said crossbar, a compression means dis-

70 75

posed on said leg element and bearing against said stop, a movable leg member having a fabric engaging end portion at one end thereof and a laterally extending portion at its other end, said leg portions being formed to provide substantial face portions upon its outer surface, a slot formed in the laterally extending portion of said movable leg member and corresponding in contour to the outer surface of said leg portions and disposed over the latter into engagement with said compression means and an abutment

5 formed at the free ends of said leg portions to retain the laterally extending portion of said movable leg member on said leg portions, said face portions on the outer surface of said leg portions coacting with the corresponding contour of the slot formed in the laterally extending portion of the movable leg member to prevent the latter from rotating relative to said leg portions.
